DeG. Fowler
Button.

Nº

Patented May 8. 1833

(See Specification)

De Cooper a Fonder, North Brimford, Connecticut.)

Specification.

The Schedule referred to in the following Patent and making part of the same, containing a description in the words of the said De Cooper Fonder himself of his improvement in the mode of manufacturing dead-wooded Buttons, being an improvement on his former Patent dated 13 June 1831.

To all persons to whom these presents shall come, know ye that I, De Cooper a Fonder, of North Brimford in the County of New Haven and State of Connecticut, a citizen of the United States, have invented, contrived and applied to make a new and useful improvement upon my former Dead-wooded Buttons, which I specify and describe in manner follows:

Instead of howevering the common wood Buttons in the manner now described by me in my former Patent, granted me by the United States for that purpose of law and bearing date the thirteenth day of June 1831, I knock out the Core, or portion removed, as in Record in the Office of the Secretary of State of the United States, upon a description of my former Patent, and by such ultimate means to make said former Patent and Specification of record good for ever, that the whole face of the button with the latter substance thereof, and for a row whether the same be tin, copper, brass, or other metal, & then punch two or three semicircular holes through the same or pass through the wood, beneath. I have several in found so that the thread or cord by which the button is made fast will pass thru the metal, & also thru the wood. The whole operation being as follows: having the old button broken and which had a core, and out of the center thereof to pass the whole face of the button, and over the back thereof, which is done by smelting to cut out the central part and using the whole plan for finishing the holes thru the tin and wood both & not thru the wood only as before. The edge of the tin or other metallic substance will be turned under or work into the wood, so as to leave the hole thru the metal correctly made. Then the whole button will be stronger, more tightly fastened, and lighter & easier in the manufacture. What I

15121

claim as my improvement on my former Patent, consisting of placing
and running the back of the die-dug Wood Button, instead of running
the front and back edges as before, in punching or forming the holes thro'
the frame and wood, and not thro' the wood only as before, and it is only
this difference in the manufacture and structure of the button for
which I ask a Patent. — I do testimony that the foregoing is a true
specification of my said improvement as above described. I have hereunto set
my hand this second day of May One thousand Eight Hundred & thirty
two, and in case of drawing I have ~~omitted~~ a button made ac-
cording to my former Patent, and also my improved button for which
I ask the present Patent.
